UNITED STATES PATENT OFFICE.

MARY I. ENGLISH, OF WASHINGTON, DISTRICT OF COLUMBIA.

GARTER.

1,046,283.

Specification of Letters Patent.

Patented Dec. 3, 1912.

Application filed July 17, 1911. Serial No. 639,053.

To all whom it may concern:

Be it known that I, MARY I. ENGLISH, a citizen of the United States, residing at Washington, in the District of Columbia, 5 have invented certain new and useful Improvements in Garters, of which the following is a specification.

This invention relates to improvements in garters for supporting stockings and has for 10 its object to provide a garter which is adapted to securely hold the stocking in position and at the same time permit free movement of the leg, without liability to tear the stocking.

15 The novel features of the invention will be apparent from the following description, taken in connection with the accompanying drawings, in which,

Figure 1 illustrates the garter as worn; 20 Fig. 2 illustrates the back of the knee, showing the arrangement of the garter as worn; Fig. 3 is a perspective view of the garter.

In the drawings, the numeral 10 indicates the leg of the wearer, the stocking being 25 shown as extending above the knee to point indicated by the numeral 11. A strip of elastic material encircles the leg above the knee and forms the band, 13, the ends of the strip being crossed at the back of the knee, 30 as shown at 14, and brought around the leg below the knee and secured together. The band, 13, has arranged thereon the slides, 15, which are provided on their upper side with loops, 16, adapted to be connected with supports, 17, which are secured to a garment 35 of the wearer. These buckles are normally arranged on opposite sides of the leg and may be adjusted to any desired position.

One end of the strip has secured thereto a 40 pad, 18, to which are fastened the members, 19 and 20, which carry the buttons, 21 and 22, respectively. The other end of the strip is formed with a loop, 23, by means of a buckle, 24, to which the end of the strip is 45 secured and which is adapted to slide along

the strip. A member, 25, is connected with the loop, 23, and engages the button, 21.

A strip, 26, has at its upper end a loop, 27, which surrounds the band, 13, and is adapted to slide on said band to any suitable position. The lower end of the strip 26 has secured thereto a member, 28, which engages the button, 22.

As thus constructed, the garter is adapted to be adjusted to different lengths and on account of its encircling the leg both above and below the knee, the stocking will be securely held, by frictional engagement, against downward displacement. The supports, 17, hold the garter in proper position and the strip 26 maintains the proper spacing between the bands.

Having thus described my invention, what I claim is:

1. A garter comprising bands adapted to encircle the limb of the wearer above and below the knee, means for adjusting the effective length of the bands, and means connecting the bands together, said connecting means having a sliding connection with one band and a readily detachable connection with the other band.

2. A garter comprising an extensible strip of fabric adapted to be arranged in the form of bands encircling the limb of the wearer above and below the knee, means slidable on the band above the knee for connecting the same with a garment of the wearer, means for detachably connecting the ends of the strip together, and means for connecting the bands together, said connecting means having a sliding connection with the upper band and a readily detachable connection with the lower band.

In testimony whereof I affix my signature in presence of two witnesses.

MARY I. ENGLISH.

Witnesses:

JAMES A. WATSON,
ARTHUR L. BRYANT.
